UNITED STATES PATENT OFFICE.

MAHLON HAMLIN, OF CATAWISSA, PENNSYLVANIA, ASSIGNOR TO THE HAMLIN CAR WHEEL AND MANUFACTURING COMPANY, OF SAME PLACE.

SECTIONAL GRATE.

SPECIFICATION forming part of Letters Patent No. 430,943, dated June 24, 1890.

Application filed January 14, 1890. Serial No. 336,907. (No model.)

To all whom it may concern:

Be it known that I, MAHLON HAMLIN, a citizen of the United States, residing at Catawissa, Columbia county, and State of Pennsylvania, have invented certain new and useful Improvements in Sectional Grates, of which the following is so full, clear, and exact description as will enable others skilled in the art to which my invention appertains to make and use the same, reference being had to the accompanying drawings, in which—

Figure 1 is a longitudinal section of my improved grate and its support. Fig. 2 is a top plan view of one of the sections. Fig. 3 is a detail end view of the support. Fig. 4 is an end elevation of one of the sections.

The object of my invention is to provide a grate and grate-support by the use of which the greatest amount of complete combustion of the fuel will be obtained with the least waste of fuel and material and with the least expense of material in the grate and its support and of fuel used.

Another object of my invention is to provide a grate by the use of which there will be no dead spots in the bed of coals on the grate.

To this end my invention consists in the novel construction and arrangement of parts, which will be hereinafter explained, and particularly pointed out in the claims at the end of the specification.

In the accompanying drawings, A designates the grate-support, which consists of a longitudinal truss provided with depressions a, adapted to fit over supports for the same.

B designates the end sections of the sectional grate.

C designates the central section of the sectional grate.

The grate-support A is provided with vertical flues D D, the upper ends of which are surrounded by projecting bosses E E. The lower face of the grates are in each instance provided with projecting perforated bosses or sockets F F, which are adapted to slip down over the bosses E.

The sections of the grate are provided with

flues G G, which register with the vertical flues D D in the grate-support, as shown 50 clearly in Fig. 1.

The tops of the sections B and C, respectively, are provided with depressions b b, which fit over corresponding projections c c, to secure them against accidental displacement at 55 the end.

The sections B B and C are provided with grooves on their upper faces which radiate from the perforations G in the sections to the longitudinal slots I I or x x, as shown in Fig. 60 2. The advantages of such construction are obvious, for should the perforations G become covered with coal the grooves will allow of the free passage of the air.

From the foregoing it will be seen at a glance 65 that the fuel used will be subjected to a direct draft from below through the perforations I I and through the perforations D D and G G, thus insuring complete combustion throughout the bed of coals on the grate.

I do not wish to be understood as limiting myself to the exact construction and proportion shown, as the same may be varied without departing from the spirit of my invention and without interfering with its usefulness.

Having described the objects, uses, and advantages of my device, what I desire to secure by Letters Patent, and what I therefore claim, is—

1. The herein-described sectional grate and support, consisting of a main truss made with vertical openings and projecting perforated bosses, in combination with sections of grate provided with bosses adapted to fit over the 85 bosses on the truss and correspondingly perforated, substantially as and for the purposes specified.

2. The herein-described sectional grate and support, consisting of a truss provided with 90 projecting bosses on the top and supplemental projections at the end, in combination with sections of grate provided with a boss corresponding with the bosses on the truss and adapted to engage therewith, and supplemental depressions to engage with the sup-

plemental projections at the end of the grate, and suitable air-passages to admit of a draft from beneath, substantially as and for the purpose specified.

- 5 3. The combination of a truss provided with vertical openings and a section of grate provided with a corresponding opening and having radiating grooves extending from the upper portion of the opening in the grate out-

ward away from said opening, substantially as and for the purpose specified.

In testimony whereof I affix my signature in the presence of two witnesses.

MAHLON HAMLIN.
